UNITED STATES PATENT OFFICE.

JOHN J. CREEDON, OF MOLINE, ILLINOIS, ASSIGNOR OF ONE-HALF TO
HERBERT W. COOPER, OF MOLINE, ILLINOIS.

HARNESS-SADDLE.

SPECIFICATION forming part of Letters Patent No. 714,870, dated December 2, 1902.
Application filed July 12, 1901. Serial No. 68,036. (No model.)

To all whom it may concern:

Be it known that I, JOHN J. CREEDON, of Moline, in the county of Rock Island and State of Illinois, have invented certain new and useful Improvements in Harness-Saddles, of which the following is a specification.

This invention relates to improvements in harness-saddles, and has for its object to provide a simplified and improved construction 10 in the means whereby the skirts or those members of the harness which connect the saddle-pad with the belly-band are detachably united with the harness-saddle.

The invention consists in the matters hereinafter described and more particularly pointed out in the appended claim, and the same will be readily understood from the following description, reference being had to the accompanying drawings, in which—

20 Figure 1 is a top plan view of a harness-saddle and attached parts embodying my invention. Fig. 2 is a rear elevation, with parts in longitudinal sections, of the same. Fig. 3 is a view similar to Fig. 2 of a modified construction.

Referring to the drawings, 1 1 designate the two saddle-pads, made of the usual shape and general construction and united at their upper ends by means of a reduced portion 2, 30 and 3 designates as a whole the yoke, which is secured to overlie the meeting end portions of the pads 1 1 and carries the usual check-rein-hook 4. Between the pads 1 1 and the yoke and connected parts is interposed the usual housing or saddle strap 5, which desirably is of a length to extend at each end somewhat beyond the ends of the saddle-pads, as indicated at 6.

Describing now more particularly the means 40 whereby the skirt members are secured to the harness-saddle, which feature constitutes the present invention, 7 7 designate jockey-plates, each constructed to underlap and extend at its upper end beneath the end of the yoke, as indicated at 8, the extreme end of each jockey-plate being apertured and secured to the body of the pad by means of a screw 9 inserted therethrough and into the pad, as indicated clearly in the drawings. 45 50 As a means of securing the jockey-plate to the lower end of the yoke in such a manner

as to afford a certain amount of flexibility or hinge motion, the plate 7 is provided in its outer surface with a transversely-extending groove 10, and the meeting end of the yoke 55 is provided with a round transverse bar-like portion 11, arranged to rest within said groove 10. Immediately above the bar portion of the yoke and the grooved portion of the jockey-plate, respectively, are formed 60 apertures or slots 12 13, which register with each other when the parts are united.

14 designates as a whole a locking-plate which is arranged to rest upon the jockey-plate and is provided at its upper end with a 65 hook member 15, suitably shaped to extend down through the openings 12 13 of the yoke and jockey-plate and provided at its extreme end with a lip 16, which underlies that part of the jockey-plate forming the margin of the 70 aperture 13 and prevents disengagement of the locking-plate except by a movement produced by lifting up its opposite end. That portion of the locking end of the plate which overlies the bar 11 is grooved or suitably 75 shaped to receive said bar, as indicated at 17, so that what amounts to a hinge connection is formed between the jockey-plate and the overlying locking-plate on the one side and the yoke upon the other. 80

Through the central portion of the locking-plate is formed an aperture 18 to accommodate the shank 20 of the terret-ring 19, which shank is threaded into the pad-iron 20' of the saddle-pad in the usual manner, and thus 85 serves to secure the locking-plate rigidly to the jockey-plate. The lower end of the jockey-plate is suitably formed to provide a loop or socket 21, adapted to receive the end of the skirt 22, and through the upper side of said 90 loop portion is formed an aperture 23, through which extends a stud 24, formed integrally upon the lower side of the locking-plate 14, said studs being of suitable length to extend entirely through the socket portion of the 95 jockey-plate, and thus through the inserted end of the skirt 22, which is suitably apertured to receive said stud. The lower side 25 of the stud 24 is suitably curved to facilitate its entrance and engagement with the 100 skirt after the opposite end of the jockey-plate has been engaged with the yoke, while

the opposite or upper side 26 is made somewhat concave, as indicated, to insure a more positive engagement between said stud and the skirt and to obviate any tendency of the 5 strain upon the skirt to lift or force the stud outwardly.

It will be seen from the foregoing description that the yoke and jockey-plate are securely united by what amounts to a hinge 10 connection and at the same time the skirt securely attached to the saddle-pad by the simple insertion and adjustment of the locking-plate to a position and subsequent screwing in of the terret-ring. By means of this construction not only is the time required to 15 assemble the parts very materially lessened, but the use of independent screws or bolts for attaching the skirts to the harness-saddle is obviated and the consequent accidental 20 loss and coming loose of such parts entirely avoided. The construction, furthermore, is such that the parts may be disconnected with the utmost facility without the use of any tools, since the terret-ring may be unscrewed 25 by hand, thereby releasing the locking-plate, so that it may be lifted out and the parts readjusted or repaired with the greatest facility.

Although I deem the construction hereinbefore described, in which the stud 24, which 30 engages the skirt, is made integral with the locking-plate, preferable, yet it will be obvious that this stud may be made as a separate member and the locking-plate employed as a means of positively preventing its accidental 35 working loose and displacement. I have accordingly shown in Fig. 3 a modification in which 24' designates the stud, made in the form of an ordinary screw inserted through the jockey-plate and threaded into the pad- 40 iron, while the lower end of the locking-plate

14' is made smooth upon its under side and arranged to underlie the outer end of said screw-stud. In other respects the construction is substantially identical with that hereinbefore described and need not, therefore, be 45 further detailed.

While I have herein described what I deem to be preferred embodiments of my invention, yet it will be obvious that the details thereof may be varied to a certain extent 50 without departing from the spirit of my invention. I do not, therefore, wish to be limited to the precise details of construction shown except to the extent that the same are made the subject of a specific claim. 55

I claim as my invention—

In a harness-saddle, the combination with the back pads and the yoke arranged to overlie said pads, of a jockey-plate socketed to receive the harness-skirt and arranged to extend at its upper end beneath the end of the yoke, interfitting hinge-like portions upon said meeting parts, apertures formed through said parts in register with each other and means for detachably uniting said jockey- 65 plate and yoke and for simultaneously securing the skirt, comprising a locking-plate provided with a hooked portion arranged to extend through said registering apertures and provided also at its end remote from the 70 hooked portion with a stud adapted to extend through the upper side of the jockey-plate and into the subjacent skirt, and a terret-ring inserted through said locking-plate and threaded into a subjacent part of the pad, 75 substantially as described.

JOHN J. CREEDON.
